UNITED STATES PATENT OFFICE.

JAMES D. DAUGHERTY, OF KITTANNING, PENNSYLVANIA, ASSIGNOR TO UNION TYPE-WRITER COMPANY, OF ILION, NEW YORK, A CORPORATION OF NEW YORK.

TYPE-WRITING MACHINE.

1,018,811.

Specification of Letters Patent.

Patented Feb. 27, 1912.

Application filed November 16, 1911. Serial No. 660,558.

To all whom it may concern:

Be it known that I, JAMES D. DAUGHERTY, a citizen of the United States, and resident of Kittanning, in the county of Armstrong 5 and State of Pennsylvania, have invented certain new and useful Improvements in Type-Writing Machines, of which the following is a specification.

My invention relates to typewriting machines and more particularly to type actions.

My present invention generally stated has some of the same general objects in view as the constructions disclosed in my previously filed applications, Serial Nos. 283,758, 15 423,948 and 614,873. In the present construction I contemplate not only providing a type action that affords an easy start with the gradual acceleration of the type bar as it approaches the printing position and which 20 gives a uniform or substantially uniform leverage and dip of the keys throughout the system, but I also provide means for preventing the levers which rock on the fulcrum from jumping away from the fulcrum and 25 for effecting a quick return of the type bar from the printing position.

To the above and other ends which will hereinafter appear my invention consists in the features of construction, arrangements 30 of parts and combinations of devices to be set forth in the following description and particularly pointed out in the appended claims.

In the accompanying drawings wherein 35 like reference characters indicate corresponding parts in the various views, Figure 1 is a fragmentary vertical sectional view taken fore and aft of the machine and centrally thereof, the view showing a sufficient number 40 of parts of a typewriting machine to illustrate my invention in its embodiment therein. Fig. 2 is a fragmentary diagrammatic plan view of the actuating devices for a number of type bars, the type bars being 45 omitted. Fig. 3 is a fragmentary diagrammatic front elevation showing portions of a number of the type actions. Fig. 4 is a bottom plan view partly in section showing four key levers and the associated sub-levers, 50 the section being taken on the line $x-x$ of Fig. 1 and looking in the direction of the arrow at said line. Fig. 5 is a fragmentary front elevation with parts in section of a key lever, sub-lever and actuating link.

55 I have shown my invention embodied in

the present instance in a front-strike typewriting machine, though from certain aspects of the invention it may be embodied in other styles of typewriting machines.

The frame of the machine comprises a 60 base 1, corner posts 2 and a top plate 3. Key levers 4 of the second order are all fulcrumed on a fulcrum bar 5 fixed to the base of the machine and may if desired be guided by suitable guide combs 5^a and 5^b. As will 65 be seen from an inspection of Fig. 2 all of the key levers are fulcrumed in a straight line extending transversely of the machine. The key levers have a fanning arrangement 70 and project forwardly to different distances in the keyboard where they are provided with finger keys 6, 7, 8 and 9, the finger keys 6 being connected to the shortest key levers and such keys being arranged in a rear bank. The keys 7 are connected to the next longest 75 key levers and these are all arranged in the second bank of keys and so on, the keys 9 being connected to the longest key levers. Contractile returning springs 10 are connected to the key levers, each spring being 80 connected at one end to a plate 11 and at its opposite end to a key lever. An upwardly extending ear or projection 12 is formed on each key lever, the various projections extending in a straight line across 85 the machine as indicated by the dotted line y in Fig. 2. An angular sub-lever, designated as a whole by the reference numeral 13, is pivoted at 14 to each of the key levers. These angular sub-levers are preferably 90 formed of two thin plates 15 (see Fig. 5) which are alike in outline and are riveted together at 16 so as to form in effect a single piece sub-lever. The plates 15 which constitute the sub-levers are spaced apart at 17 to receive the ear 12 on the associated key lever, as shown in Figs. 1 and 5. The plates are also separated at 18 to receive one end 95 of a pull link 19 pivoted to each sub-lever at 20. Except at 17 and 18 the plates 15 of each sub-lever are held in contact with each other by the rivets 16 which unite the plates. Each of the sub-levers comprises a rearwardly extending rocker arm 21 arranged 100 above a substantially horizontally disposed fulcrum plate 22 fixed to the frame of the machine. Each arm 21 has a curved contact tread 23 which is adapted to bear with a rolling action on the upper side of the fulcrum plate 22. A rearwardly extending 105

rocker arm 24 is likewise provided on each angular sub-lever, such arm extending beneath the fulcrum plate 22 and having a contact face or tread 25 adapted to cooperate with the fulcrum plate on the under side thereof. It will be understood therefore that each sub-lever is in the nature of a bifurcated lever, the two arms 21 and 24 formed by the bifurcation being substantially horizontally disposed and extending above and below the fulcrum plate 22 and cooperating with the fulcrum plate on opposite sides thereof. In addition each sub-lever 13 is provided with an upwardly extending arm 26, to the upper end of which a pull link 19 is pivoted, as hereinbefore described. The arms 26 of the sub-levers extend to different heights from the center to the sides of the system as indicated in Figs. 1 and 3.

The substantially horizontally disposed pull links 19, which extend rearwardly from the upright arms of the sub-levers, are segmentally arranged to correspond to the segmental arrangement of a series of type bars 27, each type bar being pivoted at 28 to a type bar segment 29. The type bars are thus pivoted to swing upwardly and rearwardly and to strike against the front face of a platen 30 carried by a carriage in the usual manner and diagrammatically illustrated in Figs. 1 and 3. The rear end of each link 19 is pivoted at 31 to the heel of the associated type bar whereas the forward end of the link is connected to the associated sub-lever as hereinbefore explained, the sub-lever being arranged beneath the type bar and forward of the pivot thereof. By this construction a forward movement of the arm 26 from normal position moves the type bar to the printing point by a forward pull on the link 19.

From an inspection of Fig. 2 it will be observed that the sub-levers 13 have a fanning arrangement or are arranged in diverging planes at the sides of the machine which correspond to the diverging arrangement of the key levers so that each sub-lever moves in the same plane as its associated key lever. It will also be observed that the upright arms 26 of the sub-levers are devoid of lateral bends. It will be understood therefore that by connecting the sub-levers to the diverging key levers in the manner shown the width of the system of sub-levers at the upper ends of the upright arms 26 thereof corresponds substantially to the width of the system of type bars, so that substantially a direct fore and aft pull is effected from the upper end of each sub-lever to the corresponding type bar and side or lateral strain on the parts is reduced to a minimum.

From an inspection of Fig. 2 it will be observed that the fulcrum plate 22 which is received between the rocker arms 21 and

24 is curved at its rear edge as indicated at 32 and coiled contractile returning springs 33 extend downwardly and rearwardly from the rear ends of the rocker arms 21 of the sub-levers to connect with perforated ears 34 which project upwardly from the key levers, so that each returning spring 33 is connected at one end to a key lever and at its opposite end to a perforated ear 35 formed on the arm 21 of the associated sub lever and that the ends of each spring are moved away from each other during the depression of the associated finger key.

From a consideration of Figs. 1 and 4 it will be observed that the rocker arms 21 have cut-outs 36 therein intermediate the free ends of the arms and the point of connection between the sub-lever and the key lever, or the point where power is applied to actuate the sub-lever. These cut-outs vary for different sub-levers so as to vary the length of the treads 23 or terminate the forward portion thereof at different points, the forward termination of each of such treads being indicated at 37. By this arrangement the extent or rocking action of different sub-levers on their treads 23 varies. Moreover, it will also be observed that the sub-lever arms 21 gradually increase in length from the center to the sides of the system. In other words, the arms 21 increase in length at the same ratio that the upright arms 26 increase in length from the center to the sides of the system. By this arrangement the lever arms 21 are increased in length proportionately to the arms 26 as the sides of the system are approached. Furthermore, it will be observed from an inspection of Fig. 1 that the initial point of contact between the rolling contact faces 23 on the lever arms 21 varies with the different sub-levers. In short, the point of initial contact of the treads 23 on the fulcrum plate extends gradually nearer the rear of the machine as the sides of the system are approached. By this arrangement and by the variation in the lengths of the tread, hereinbefore referred to, I am enabled to provide a uniform dip of keys and a uniform leverage throughout the system without affecting the easy start provided at the first part of the key depression and the gradual acceleration of the type bar in its movement to the printing position. In order to indicate this acceleration I have shown a key 7 in five different positions as indicated at a, b, c, d and e and these different positions are spaced at equal distances apart. The positions assumed by the type bar at these different points in the depression of the key are indicated at a, b, c, d and e. It will be seen therefore that substantially three-quarters of the key stroke is required to move the type bar from the positions shown at a to that indicated at d, 130

whereas the movement of the type bar from the position indicated at *d* to the printing position indicated at *e* is effected at the last quarter of the key stroke.

- 5 The variation in length of the different key levers is compensated for by the variation in the length of the contact treads 23. Thus from an inspection of Fig. 4 it will be seen that the sub-lever for the shortest key lever of the group shown has the shortest tread, the forward terminal 37 of such sub-lever being nearest the rear of the machine, whereas the sub-lever for the longest key lever has an extent of tread which extends throughout, or substantially throughout, the length of the lever arm 21 and so on. The other treads 23 are varied in proportion to the length of the key levers which are co-operative with the sub-levers carrying such treads. There being four lengths of key levers throughout the system it will be seen from Fig. 4 that the treads 23 have four different lengths to compensate for the difference in leverage due to the variation in the length of the key levers. It will be seen therefore that the variation in the treads 23 compensates for the variation in the lengths of the key levers, whereas the variation in the lengths of the lever arms 21 and the variation in the point of initial engagement between said lever arms and the fulcrum plate compensate for the variation in the lengths of the upright arms 26, which arms become gradually longer as they approach the sides of the system, and a uniform leverage and a uniform extent of dip of the keys is provided throughout the system. It will also be observed that the lever or rocker arms 24 arranged beneath the fulcrum plate 40 22 vary in length in accordance with the variation in length of the lever arms 21 in order that the contact edges 25 on the arms 24 may properly co-operate with the under face of the fulcrum plate.
- 45 As a key is depressed the associated sub-lever will be rocked, causing the contact between the tread 23 thereon and the fulcrum plate to approach the point of pivotal connection between the sub-lever and key lever. 50 At the same time the arm 24 of the lever is rocked but it is at all times or substantially at all times, maintained in co-operative relation with the under side of the fulcrum plate 22 without, however, in any manner affecting the operation of the sub-lever except to insure a maintenance of the contact tread 23 on the fulcrum plate and prevent the sub-lever from jumping away from the fulcrum plate. Moreover, when the type 55 strikes the platen a pressure is exerted by the arm 24 against the fulcrum plate to effect a quick restoration of the type bar and the actuating devices connected therewith to normal position and to assure a speedy 60 movement of the type bar away from the
- printing position. It will also be seen that the pull effected by the springs 33 tends to pull and maintain the arm 21 of the associated sub-lever down on the fulcrum plate and to lift the associated key lever to restore 70 it and the type bar to normal position. As the points of connection at opposite ends of a spring 33 are separated during the depression of a key, the pull of the spring is exerted at all times to restore the parts to normal position. In practice the spring 33 may be found to be sufficient to restore the key levers to normal position, though I prefer, as a matter of precaution, to employ the restoring springs 21 to assure the proper restoration of the key levers. 75
- 80 It will be observed that I have shown two types on a bar in the present instance and while from certain aspects of my present invention it is immaterial how many types 85 are carried on a bar; or whether a relative case shifting movement between the type bars and platen is effected; or whether the platen or type bars be shifted, nevertheless, 90 it will be understood that the construction is such that it readily lends itself to a machine in which the type bar segment is shifted to change the "case" position of the bars relatively to the platen. 95
- Various changes may be made without departing from the spirit and scope of my invention.
- What I claim as new and desire to secure by Letters Patent, is:-
1. In a typewriting machine, the combination of a type bar; a finger key; and intermediate actuating connections between said finger key and type bar, said connections comprising an actuating lever having two rocker arms, and a fulcrum plate intermediate said rocker arms and against which both of said rocker arms bear. 100
  2. In a typewriting machine, the combination of a type bar; a key lever; and intermediate actuating connections between said key lever and type bar, said connections comprising a sub-lever having two rocker arms, and a fulcrum plate intermediate said rocker arms and against which both of said rocker arms bear. 110
  3. In a typewriting machine, the combination of a type bar; a finger key; and intermediate actuating connections between said finger key and type bar, said connections comprising an actuating lever having two rocker arms, a fulcrum plate intermediate said rocker arms and against which both of said rocker arms bear, and a pull link intermediate said actuating lever and type bar. 120
  4. In a typewriting machine, the combination of a type bar; a key lever; a sub-lever operatively connected with said key lever, said sub-lever having two rocker arms; a fulcrum plate between said rocker arms; a fulcrum plate 130

arms and against which both of said arms bear; and a pull link between the sub-lever and type bar.

5. In a front-strike typewriting machine, 5 the combination of an upwardly and rearwardly striking type bar; a key lever of the second order; a sub-lever pivoted directly to said key lever, said sub-lever having two rocker arms; a fulcrum plate between said 10 arms and with which said arms coöperate; and means for connecting said sub-lever and type bar.

6. In a front-strike typewriting machine, 15 the combination of an upwardly and rearwardly striking type bar; a key lever of the second order; a sub-lever arranged forward of the pivoted end of the type bar and pivoted directly to said key lever, said sub-lever having two rocker arms; a fulcrum 20 plate between said arms and with which said arms coöperate; and a pull link connecting said sub-lever and type bar.

7. In a typewriting machine, the combination of a type bar; a key lever; and intermediate actuating connections between said 25 key lever and type bar, said connections comprising a sub-lever having two rocker arms, a fulcrum plate intermediate said rocker arms and against which both of said 30 rocker arms bear, and a contractile returning spring connected at one end to said key lever and at its other end to one of said rocker arms.

8. In a front strike typewriting machine, 35 the combination of an upwardly and rearwardly striking type bar; a key lever; a sub-lever pivoted directly to said key lever, said sub-lever having two rocker arms; a fulcrum plate between said arms and 40 against which both of said arms bear; means for connecting said sub-lever and type bar; and a contractile returning spring connected at one end to said key lever and at its other end to one of said rocker arms.

45 9. In a front strike typewriting machine, the combination of an upwardly and rearwardly striking type bar; a key lever of the second order; a sub-lever arranged forward of the pivoted end of the type bar and pivoted directly to said key lever, said sub-lever having two rocker arms; a fulcrum plate between said arms and with which said arms coöperate; a pull link directly connecting said sub-lever and type bar; and a 50 contractile returning spring connected at one end to one of said rocker arms and extending downwardly and rearwardly therefrom to the key lever to which the other end of said spring is connected.

60 10. In a typewriting machine, the combination of a series of upwardly and rearwardly swinging type bars; a series of key levers; intermediate actuating connections between said key levers and type bars, said 65 connections comprising a series of sub-levers

each having two rocker arms; and a fulcrum plate between said rocker arms and against which both of said rocker arms bear to afford an acceleration of each type bar in its movement to printing position and a quick 70 return of the type bar.

11. In a typewriting machine, the combination of a series of upwardly and rearwardly swinging type bars; a series of fanning key levers; intermediate actuating connections between said key levers and type bars, said connections comprising a series of sub-levers that have a fanning arrangement which corresponds substantially to the fanning arrangement of the key levers, and each 75 of said sub-levers having two rocker arms; and a fulcrum plate between said rocker arms and with which the rocker arms are coöperative.

12. In a typewriting machine, the combination of a series of upwardly and rearwardly swinging type bars; a series of key levers of the second order; intermediate actuating connections between said key levers and type bars, said connections comprising a series of sub-levers pivoted directly 85 to said key levers and each having two rocker arms; and a fulcrum plate between said rocker arms and with which the rocker arms are coöperative one on the top and the other 90 on the bottom of said fulcrum plate to afford an acceleration of each type bar in its movement to printing position and a quick return 95 of the type bar.

13. In a typewriting machine, the combination of a series of upwardly and rearwardly swinging type bars; a series of fanning key levers of the second order; intermediate actuating connections between said key levers and type bars, said connections comprising a series of sub-levers pivoted directly to said key levers and having a fanning arrangement which corresponds substantially to the fanning arrangement of the key levers, each of said sub-levers being provided with two rocker arms, a fulcrum plate between said rocker arms and with which the rocker arms are coöperative, and a series 100 of links interposed between said type bars and sub-levers.

14. In a typewriting machine, the combination of a series of upwardly and rearwardly swinging type bars; a series of fanning key levers of the second order; intermediate actuating connections between said key levers and type bars, said connections comprising a series of sub-levers pivoted directly to said key levers and having a fanning arrangement which corresponds substantially to the fanning arrangement of the key levers, each of said sub-levers being provided with two rocker arms, a fulcrum plate between said rocker arms and with which the rocker arms are coöperative, a series of links interposed between said type bars and 110

- sub-levers, and a series of contractile returning springs each connected at one end to one of said rocker arms and connected at the other end to a key lever.
- 5 15. In a front-strike typewriting machine, the combination of a series of upwardly and rearwardly swinging type bars; a series of fanning key levers; a series of sub-levers arranged forward of the pivoted ends of the 10 type bars and pivoted directly to said key levers, said sub-levers having a fanning arrangement which corresponds substantially to the fanning arrangement of the key levers, and each sub-lever having two rocker 15 arms; a fulcrum plate between the rocker arms and with which the rocker arms co-operate; pull links connecting the type bars and sub-levers; and contractile returning springs each connected at one end to a sub- 20 lever and at its other end to a key lever.
16. In a typewriting machine, the combination of a series of type bars; a series of finger keys; and intermediate actuating connections between the finger keys and type 25 bars, said actuating connections comprising levers each having a rocking arm, said rocking arms having tread portions extending for only a part of their lengths thereof, the remainder of said arms being cut away variable extents between said treads and the pivotal ends of said arms, and a fulcrum plate on which said treads rock, the tread portions being normally in contact with the fulcrum plate near the free ends of the arms 30 and terminating at the opposite ends of the treads at varying points depending on the extents of the cut-outs.
17. In a typewriting machine, the combination of a type bar; a key lever of the 40 second order; and intermediate actuating connections between the key lever and type bar, said actuating connections comprising a sub-lever pivoted to said key lever intermediate the ends thereof and having a rocking arm, a fulcrum plate on which said arm rocks, the tread of the arm extending for only a portion of the arm's length and normally bearing near its free end on said plate and the rocking arm being cut away between 45 its tread portion and the point of pivotal connection with the key lever, to determine the extent of rocking motion that the sub-lever has on its fulcrum.
- 50 18. In a typewriting machine, the combination of a series of type bars; a series of finger keys; intermediate actuating connections between said finger keys and type bars, said connections comprising a series of levers each having a rocker arm to rock on the fulcrum of said lever and afford an accelerated movement of the associated type bar in its approach to the printing position, said rocker arms having cut-out portions of varying extents intermediate the free ends 55 thereof and points where power is applied, to vary the extent of the rocking action of the different levers.
19. In a typewriting machine, the combination of a series of type bars; a series of key levers; intermediate actuating connections between said key levers and type bars, said connections comprising a series of sub-levers connected with said key levers and each having a rocker arm to rock on the fulcrum of said sub-lever and afford an accelerated movement of the associated type bar in its approach to the printing position, said rocker arms having cut-out portions of varying extents intermediate the free ends thereof and points of connection between the key levers and the sub-levers, to vary the extent of the rocking action of the different sub-levers. 70
20. In a typewriting machine, the combination of a series of type bars; a series of key levers; a series of sub-levers having actuating arms of varying lengths, each of said sub-levers having two rocker arms; and a fulcrum between said rocker arms and against which both of said rocker arms 75 bear, the length of the rocker arms increasing proportionately to the increase in the length of the actuating arms. 80
21. In a typewriting machine, the combination of a series of type bars; a series of key levers of varying lengths; a series of sub-levers, each of said sub-levers having two rocker arms; and a fulcrum between said rocker arms and with which the rocker arms co-operate, the length of the rocker 85 treads varying to compensate for the variation in the length of the key levers. 90
22. In a typewriting machine, the combination of a series of type bars; a series of key levers of varying lengths; a series of sub-levers having actuating arms of varying lengths, each of said sub-levers having two rocker arms; and a fulcrum between said rocker arms and with which the rocker arms co-operate, the length of the rocker 95 arms increasing proportionately to the increase in the length of the actuating arms, and the rocker treads varying to compensate for the variation in the length of the key levers. 100
23. In a front strike typewriting machine, the combination of a series of upwardly and rearwardly swinging type bars adapted to strike against the front face of the platen; a series of key levers; a series of intermediate actuating connections between said key levers and type bars, said connections comprising a series of sub-levers having upright actuating arms that increase in length from the center to the sides of the system and each of which sub-levers has two rocker arms; and a fulcrum received between said rocker arms and against which both of said rocker arms bear. 115
24. In a front-strike typewriting ma- 130

chine, the combination of a series of upwardly and rearwardly swinging type bars adapted to strike against the front face of the platen; a series of key levers; a series 5 of intermediate actuating connections between said key levers and type bars, said connections comprising a series of sub-levers having upright actuating arms that increase in length from the center to the sides of the system, and each of which sub-levers has two rocker arms; and a fulcrum received between said rocker 10 arms and with which the rocker arms co-operate, the rocker arms increasing in length from the center to the sides of the system to compensate for the variation in the length of the upright actuating arms, and the treads on said rocker arms varying to compensate for the variation in the length of the key levers.

25. In a front strike typewriting machine, the combination of a series of upwardly and rearwardly swinging type bars adapted to strike against the front face of the platen; a series of key levers that vary 20 in length; a series of intermediate actuating

connections between said key levers and type bars, said connections comprising a 25 series of sub-levers having upright actuating arms that increase in length from the center to the sides of the system, and each of which sub-levers has two rocker arms; and a fulcrum received between said rocker 30 arms and with which the rocker arms co-operate, the rocker arms increasing in length from the center to the sides of the system to compensate for the variation in the length of the upright actuating arms, and the 35 treads on said rocker arms varying to compensate for the variation in the length of the key levers.

Signed at Kittanning, in the county of Armstrong and State of Pennsylvania, this 40
9th day of November, A. D. 1911.
